UNITED STATES PATENT OFFICE.

HARVEY FELDMEIER, OF LITTLE FALLS, NEW YORK, ASSIGNOR TO D. H. BURRELL & COMPANY, OF LITTLE FALLS, NEW YORK.

CENTRIFUGAL LIQUID-HEATER.

1,186,175.

Specification of Letters Patent. Patented June 6, 1916.

Application filed May 23, 1912. Serial No. 699,266.

To all whom it may concern:

Be it known that I, HARVEY FELDMEIER, a citizen of the United States, residing at Little Falls, in the county of Herkimer and State of New York, have invented a new and useful Improvement in Centrifugal Liquid-Heaters, of which the following is a specification.

This invention relates to that class of liquid heaters which comprises a heated cylindrical vessel into which the liquid is fed at the bottom and from which it is discharged at the top, and a rotary agitator or beater which drives the liquid through the vessel in a thin layer or film by centrifugal force with a whirling motion in an upward direction, whereby the liquid is kept in close contact with the inner surface of the heated vessel and evenly distributed over the same and thoroughly heated and at the same time elevated by centrifugal force to a higher level, so that the apparatus works to a certain extent like a centrifugal pump.

The object of the invention is to produce a heater of this character which is simple in construction and efficient in operation and which can be readily taken apart for cleaning, this being an important consideration in heaters which are used for heating milk or cream in the process of pasteurization.

In the accompanying drawings: Figure 1 is an elevation of this improved heater having its axis arranged vertically. Fig. 2 is a top plan view thereof. Fig. 3 is a sectional elevation of this heater, on an enlarged scale. Fig. 4 is a plan view, partly in section, of the bottom of the heater looking upward, the section being taken on line 4—4, Fig. 3. Fig. 5 is a horizontal section through the top or delivery chamber of the heater on line 5—5, Fig. 3. Fig. 6 is a fragmentary vertical section, on an enlarged scale, of the top of the heater. Fig. 7 is a fragmentary vertical section, on an enlarged scale, of the bottom of the heater. Fig. 8 is a fragmentary side elevation of the lower portion of the heater, showing the inlet and outlet pipes for the hot water. Fig. 9 is a side elevation of the heater with its axis arranged in an oblique position. Fig. 10 is an end elevation, on a reduced scale. Fig. 11 is a fragmentary vertical section of the driving mechanism.

Like reference characters refer to like parts in the several figures.

The heater comprises a cylindrical heat-

ing vessel A, a surrounding heating jacket B which is supplied with a suitable heating medium, for instance, hot water, and an outer air jacket C which protects or insulates the heating jacket. These parts may be arranged with their axis vertically, as represented in Figs. 1, 2 and 3, but in heaters of considerable capacity or depth they are preferably arranged with their axis oblique as represented in Figs. 9-11. It has been found in practice that the capacity of such a heater can be greatly increased by increasing the length or depth of the heating cylinder or centrifugal vessel without increasing its diameter, and that the increase in capacity is much greater in proportion than the increase in length or depth of the cylinder. For illustration, a heater having a centrifugal vessel which is twelve inches in diameter and twenty inches in depth has approximately a heating capacity of about 2000 pounds of milk per hour, while a heater of the same diameter but forty inches in depth was found to have a capacity of approximately 6000 pounds of milk per hour. This is probably due to the fact that there is considerable agitation in the milk at the bottom of the heating vessel where the heater or agitator first strikes the milk, in consequence of which condition the lower portion of the heater is not as efficient as the upper portion where the milk has been reduced to a uniform film or layer which travels with great speed over the heated surface of the cylinder.

In order to render it convenient to clean a deep machine the cylinder is arranged obliquely, as represented in Figs. 9-11, and supported at its bottom by the frame 20, in which the driving mechanism is arranged, and at its top by legs 21 which are secured to the top portion of the heater. The construction of the heater, so far as the heating cylinder and its adjuncts and the rotary agitator and driving mechanism are concerned, is the same, whether the cylinder is arranged vertically or obliquely, and in order to simplify the representation the details of the construction are represented in connection with the vertical heater represented in Figs. 1-8.

The heating vessel comprises a peripheral wall or cylinder 22 and a bottom plate 23. The cylinder, which is preferably of tinned copper and stiffened by an external spiral

band 24, is secured to the upstanding flange 25 of the bottom plate by riveting and soldering. This bottom plate is secured by screws 27 or other suitable means upon a base frame 26 in which the driving mechanism is arranged.

29 represents the feed cup and 30 the feed pipe which leads from this cup to the lower portion of the heating vessel and is provided at its inner end with an elbow 31 which is secured to the underside of the bottom plate 23 and communicates with a feed opening 32 in the same. The outer end of the feed pipe is provided with a drain cock 33, Figs. 1 and 2.

34 The rotary beater or agitator comprises wings or blades 34 which are arranged within the cylindrical vessel A, near the peripheral wall 22 thereof, and secured by spiders 35 36 to an upright shaft 37. This shaft is detachably secured by coupling pins 38 or other suitable means to a driving shaft 39 which extends upwardly through the bottom 23 of the centrifugal vessel and is journaled at its upper end in a bearing 40 arranged in the upper portion of a sleeve or tubular housing 41 formed centrally on the plate 23.

42 The lower end of the upright driving shaft 39 is supported in a step bearing 42 which is arranged in the base frame 26. 43 represents a bevel wheel which is secured to the driving shaft above this step bearing and 44 represents a similar wheel which is secured to the inner end of a horizontal driving shaft 45 journaled in the base frame 26 and provided at its outer end with devices by which power is applied, for instance, tight and loose pulleys 46 47.

48 The centrifugal vessel communicates at its upper end with a delivery chamber D which is larger in diameter than the centrifugal vessel, so that the milk, as it escapes from the upper end of the centrifugal vessel, is 50 flung outwardly by centrifugal force into this delivery chamber from which it is discharged by a tangential spout or pipe 50, Figs. 1, 2 and 5. The whirling movement of the liquid is maintained in the delivery chamber by wings 51 which are secured to the upper spider 36 and which are preferably more numerous than the wings in the centrifugal vessel. The enlarged delivery chamber permits of the free escape of the milk 55 from the upper end of the centrifugal vessel and this serves to keep the whirling layer or film of milk in the vessel of substantially uniform thickness and unaffected by the head against which the milk is elevated by 60 the machine and which may be greater or less in different pasteurizer systems. Furthermore, the enlarged chamber, by reason of its greater diameter, increases the centrifugal force with which the milk is discharged and increases the elevating power

of the machine. The discharge pipe 50 communicates with the delivery chamber above the lower edges of the delivery wings 51 so that the latter operate upon the liquid in the delivery chamber and accelerate the speed thereof.

65 The delivery chamber D comprises a bottom plate 52 formed with an upwardly extending peripheral wall 53 and a cover 54 which is removably secured upon the peripheral wall by bolts 55, Figs. 3 and 6, the joint being tightened by a packing 56. The cover 54 is provided with a downwardly extending centering pin 57 which projects into the upper hollow end of the beater shaft 37 and steadies the same. Upon removing the cover the beater, comprising the shaft 37, spiders 35 and 36, and wings 34 and 51, can be withdrawn from the centrifugal vessel, leaving the inner surfaces of the latter and the delivery chamber free and unobstructed for cleaning. The cleaning can be very conveniently effected even in the case of deep centrifugal vessels if the same are arranged obliquely, as represented in Figs. 9-11. 70 The centrifugal vessel and the heating jacket can also be readily detached from each other.

75 The peripheral wall 22 of the centrifugal vessel is secured at its upper end to a downwardly projecting flange 60 formed on the bottom plate 52 of the delivery chamber D, so that this chamber is permanently connected with the centrifugal vessel.

80 The heating jacket B comprises a peripheral wall 61 which is preferably stiffened by a spiral external rib 62. The wall 61 is secured at its lower end by riveting and soldering or other suitable means to an upwardly projecting flange 63 formed on an 85 annular bottom head 64, and at its upper end to an annular top head 65 which is provided with a downwardly projecting flange 66 for that purpose. The bottom head 64 is secured to the bottom plate 23 by screws 67, Figs. 4 and 7, and a packing 68 is placed between the plate 23 and the bottom ring 64.

90 The air jacket C comprises a peripheral wall 70 which is secured at its lower end to the marginal edge of the bottom head 64 and at its upper end to the marginal portion of the annular top head 65. The latter is provided with an upwardly projecting cylindrical tongue 71 which extends into a corresponding groove 72 in the under side of the delivery chamber, in which groove the tongue can move up and down, thus forming a slip joint which permits the centrifugal vessel to expand and contract independently 100 of the inclosing heating jacket and air jacket, thereby avoiding strains under unequal expansion and contraction of the parts. A packing 73 is preferably arranged in the bottom of the groove.

105 In the heater in which the axis of the cen-

trifugal vessel is arranged obliquely, as represented in Figs. 9-11, the working parts are of the same construction as in the vertical heater and the base frame 20 is arranged 5 to support the lower portion of the centrifugal vessel and connecting parts in an oblique position.

I claim as my invention:

1. A centrifugal liquid heater, comprising 10 a cylindrical heating vessel having its axis arranged obliquely, means for heating said vessel, a rotary beater removably arranged in said vessel, a base frame supporting the lower end of said vessel and holding 15 said vessel permanently in an oblique position, driving mechanism for said beater arranged in said base frame, means for feeding the liquid to the lower end of said vessel and for discharging the heated liquid 20 from the upper portion thereof, and a removable cover applied to the upper end of said vessel, substantially as set forth.

2. A centrifugal liquid heater, comprising 25 a cylindrical heating vessel having its axis arranged obliquely, means for heating said vessel, a rotary beater arranged in said vessel, a base frame supporting the lower end of said vessel and holding said vessel permanently in an oblique position, driving 30 mechanism for said beater arranged in said base frame, and supporting legs connected with the upper portion of said vessel, substantially as set forth.

3. The combination with a centrifugal 35 heating vessel, a rotary beater arranged therein, means for feeding the liquid to the said vessel at one end and delivering the heated liquid therefrom at the other end, a surrounding heating jacket, an outer air 40 jacket, an annular head to which said heating jacket and said air jacket are secured at one end, and an annular head to which the opposite ends of said jackets are secured and which is connected with said heating 45 vessel by a slip joint, substantially as set forth.

4. The combination with a centrifugal heating vessel, a rotary beater arranged therein, means for feeding the liquid to the 50 said vessel at one end and delivering the heated liquid therefrom at the other end, a surrounding heating jacket, an outer air jacket, an annular head to which said heating jacket and said air jacket are secured 55 at one end, and an annular head to which the opposite ends of said jackets are secured and which is provided with a tongue having a sliding connection with said vessel, substantially as set forth.

5. The combination with a centrifugal 60 heating vessel, a rotary beater arranged in the same, and means for feeding the liquid

to the lower end of the vessel, of a delivery chamber arranged at the upper end of the vessel and of larger diameter than the 65 same, a rotary delivery beater arranged in said delivery chamber contiguous to the beater in the heating vessel, and a discharge pipe arranged in the peripheral wall of the delivery chamber opposite said delivery 70 beater in the plane of rotation thereof.

6. The combination with a centrifugal heating vessel, a rotary beater arranged in the same, means for feeding the liquid to the lower end of said vessel, a delivery 75 chamber arranged at the upper end of said vessel and of larger diameter than said vessel, means for discharging the liquid from said chamber, a heating jacket surrounding said vessel, an outer air jacket, a bottom 80 head to which said jackets are secured, and a top head to which said jackets are secured and which is provided with a tongue having a slip connection with said chamber, substantially as set forth.

7. The combination with a heating vessel having a closed bottom and having an overhanging top portion provided in its underside with an annular groove, a rotary beater arranged in said vessel, means for feeding 90 the liquid to the lower end of said vessel and for discharging the heated liquid from the top thereof, a heating jacket surrounding said vessel, means for securing the lower end of said vessel to said bottom, and a top 95 head to which said jacket is secured and which is provided with an annular tongue arranged loosely in said groove, substantially as set forth.

8. The combination with a centrifugal 100 heating vessel having a closed bottom, of a surrounding heating jacket, means for securing the lower end of said jacket detachably to said bottom, and a slip joint connecting the upper end of said jacket detachably to the upper portion of said vessel, substantially as set forth.

9. The combination with a centrifugal heating vessel having a closed bottom, of a surrounding heating jacket and an outer air 110 jacket, an annular bottom head to which the lower ends of said jackets are secured and which is detachably connected with the bottom of said centrifugal vessel, and an annular top head to which the upper ends 115 of said jackets are secured and which is detachably connected with said vessel, substantially as set forth.

Witness my hand in the presence of two subscribing witnesses.
